UNITED STATES PATENT OFFICE

2,008,642

FAUCET

Henry Hughes, Toronto, Ontario, Canada, assignor to The James Morrison Brass Manufacturing Company Limited, Toronto, Ontario, Canada

Application February 19, 1934, Serial No. 711,957

7 Claims. (Cl. 225—44)

This invention relates to new and useful improvements in faucets particularly adapted for application to beer kegs.

The general object of this invention is to provide a faucet for beer kegs which may be shipped with its container and to this end it may be built in the keg or applied to it at the time the container is filled with the contents to be dispensed and thus supply the consignee with a pouring or dispensing device that is immediately available for use. More particularly the faucet embodying this invention is designed so that it can be put on any keg or other suitable container, and the device is so constructed and arranged that the spout will lie flat against the head of the container and within the space provided between the head and the upper rim of the sides, and in a dispensing position it can be rotated so as to extend over the outer edge of the side. A further advantage of my invention is the incorporation in the mounting of the device of an air inlet valve extending through the mounting and through which air may be forced into the container so that air pressure may be created and maintained therein.

A still further advantage of my invention is the incorporation of a dispensing valve which may be opened or closed when the faucet is in a dispensing position and which in its non-dispensing position also provides a seat so that the spout and valve may be sealed together during shipment or storage, thus preventing the withdrawal of the contents without breaking the seal.

Other devices have been devised and constructed which may be applied to containers, such as an apparatus having a swing faucet which in a non-dispensing position rests below the upper rim of the sides, and which by swinging or turning the dispensing member into a dispensing position simultaneously brings the orifices in the dispensing member and bushing into alignment allowing the flow of liquid from the container through the dispensing member. A disadvantage of this device is that the liquid begins to flow before it reaches the dispensing position over the upper rim of the side of the keg. Similarly when it is desired to stop the flow the dispensing faucet is turned back permitting a certain amount of leakage until the orifices are out of alignment. By providing a separate dispensing valve it is possible to control the flow of the liquid and thus prevent any leakage.

Other and further advantages and objects of my invention are fully set forth in the accompanying specification and drawing in which:—

Fig. 1 is a plan view of my faucet partly in section;

Fig. 2 is a sectional view of a container with the device in place;

Fig. 3 is a rear view partly in section of my device;

Fig. 4 is a view of the turning plug; and

Fig. 5 is a fragmentary sectional view showing the bottom of the keg and the beer discharge pipe.

Like characters of reference refer to like parts throughout the specification and drawing.

For the purpose of fully illustrating the principal features of my improved faucet I have shown it in the drawing as being employed as a tapping device for a beer keg which is indicated by the numeral 1, the keg consisting of the sides 2, head 3 and bottom 4, the sides of the keg being extended above the head 3 and below the bottom 4 as is usual in the construction of such kegs. The faucet itself is mounted on the head which is below the upper rim of the sides of the keg and for this purpose a hole of the appropriate size is provided in the head into which is driven an annular housing 5, this annular housing being internally threaded for the purpose of receiving a bushing 6. The bushing is shown as being provided with a bore 7 therethrough, the lower end of the bore being narrower than the upper portion to form an annular flange 1a. The upper portion of the bore 7 is internally screw threaded for receiving the threaded tail piece of the faucet.

A liquid discharge pipe 8 extending downwardly into the barrel is entered through the bore 7 of the bushing 6. This pipe 8 carries a collar 38 of a shape and size so that it can be entered into the widened portion of the bore 7 and seats upon a gasket 31 which over-lies the flange 1a. In Fig. 2, I have shown a preferred manner of seating the collar on the gasket so that the pipe 8 will have a limited amount of play, this being accomplished by inserting a compression spring 30 within the bore of the bushing and which acts against the collar 38 and the bottom of the tail piece 9a. It is of further advantage to bend the pipe 8 so that it will be directed to and extend into the groove which is formed at the juncture of the bottom with the sides so that it is possible to withdraw all the liquid from the keg.

The faucet proper consists of a housing 9, the housing being provided with a tail piece 9a, externally threaded so that it may be secured in the bore 7. The upper portion of the housing is formed with two orifices 32, 33 tapering so that

they are narrower at one side of the housing than at the other. Extending vertically through the tail of the housing and communicating with the orifice 32 is a passageway 10 and communicating between the orifices 32 and 33 is a passageway 11. Although it is not essential it is of advantage to have the orifice 33 formed in the casing on an elevation slightly higher than the orifice 32, the advantage of which will later be made more apparent. A stop cock is mounted in the housing, the cock consisting of a turning plug 12 which is entered in the orifice 32 and is shaped to fit snugly therein, the turning plug being provided with a furrow 26 so that when the plug is turned in one position a passageway will be provided between the passageways 10 and 11 and when it is turned in another direction the passageway will be closed. The plug 12 is provided with an operating handle 13 which has its upper surface formed with a longitudinal groove 14, the free end of the handle being provided with an orifice 16^a therethrough and a slot 16. A spigot 34 is entered in the orifice 33, the spigot being shaped to fit snugly into the orifice so as to prevent leakage of liquid, and terminating in an elbow 36, the spigot being formed with a passageway 35 which communicates through the spigot with the passageway 11 and terminates at the outer extremity of the elbow. The outer extremity of the passageway is screw threaded to receive a spout 15 which is threadedly connected thereto in axial alignment with the operating handle 13, the spout 15 being provided with a nozzle 37 which is formed with an apertured lug 17 adapted to enter the slot 16 when the spout is seated in the groove 14 of the handle 13. The plug 12 and the spigot 34 are drawn tightly into place and held there by means of washers 21 which fit over the ends thereof opposite to the handle and the spout respectively and engage with the housing 5 and the head screws 22 which are threaded into their tapered ends, these ends of the plug 12 and the spout 34 being enclosed by caps 23 to prevent any access to the screws 22 for the purpose of loosening the same. It is preferable to have the outer surface of these caps highly polished so that if any attempt is made to remove them by ordinary means this surface will be damaged making it immediately apparent that the faucet has been tampered with.

The bushing 6 is also provided with an orifice 19 which has mounted therein a non-return air valve 18 so that air may be pumped into the keg for the purpose of expelling the liquid therein and when necessary for keeping the liquid therein under pressure for preserving the freshness of the contents. As an effective means for preventing tampering with the air valve during storage or shipment the nozzle has mounted thereon a member 29 which is provided with a downwardly extending skirting 29a, the member being located so that when the nozzle and handle are sealed together this member will over-lie and surround the valve preventing, during storage and shipment, any manipulation of the valve for the purpose of effecting the withdrawal of the liquid until received by the ultimate consumer. It is also preferable to so locate the air valve that it will serve to prevent the faucet being removed from the bushing when the tap and handle are sealed together and to this end it is positioned so that to turn the housing out of the bushing it is first necessary to remove the air valve.

The mounting of the faucet described is ex-

tremely simple. The first step is to bore a hole in the head and then drive in the annular ring 5 flush with the head. The bushing 6 is then threaded into the ring so that the top of the bushing comes flush with the top of the ring. The gasket 31 is then inserted in the bore of the bushing and the pipe 8 entered through the bushing with the collar resting on the gasket. The spring 30 is then inserted and the tail piece of the faucet screwed into the bore and brought to the correct position so that the member 29 will over-lie the opening 19 when the spout 15 and the handle 13 are sealed together. After these parts are assembled together the valve 18 is inserted in the orifice 19. In Fig. 2, I have shown the spout being moved from the position shown in Fig. 1 to its sealed position and it will be apparent that when the spout is sealed to the handle 13 that it is impossible to move either of these without breaking the seal as the spout and handle move on different centers to dispense liquid from the container when received by the consumer, the seal is broken and the spout turned to the position shown in Fig. 1. The handle 13 is then raised which turns the plug 12 to bring the furrow 26 in communication with the passageways 10 and 11. In Fig. 1, I have shown the handle being turned to this latter position. Whenever it is required for expelling liquid, air under pressure may be forced into the keg through the valve 18 by any suitable means such as by an air pump.

Having thus fully described my invention what I claim as new and desire to secure by Letters Patent is:

1. A faucet for liquid containers comprising a housing, a passageway through said housing, a stop cock mounted in the housing controlling the flow of liquid therethrough, a handle carried by said stop cock, a spigot mounted in the housing forward of the stop cock, a spout carried by the spigot, a passageway through said spigot and spout adapted to communicate with the first mentioned passageway when the spout is turned to its dispensing position, said spout being adapted to lie against the handle when the stop cock is in closed position and means for sealing the spout and handle in said position.

2. A faucet for liquid containers comprising a housing, a passageway through said housing, a stop cock mounted in the housing controlling the flow of liquid therethrough, a spigot mounted in the housing forward of the stop cock, a spout carried by the spigot, the spout being disposed below the rim of the container during storage or shipment and adapted to be swung over the rim of the container to a pouring position, a mounting for said housing, an air valve carried by said mounting and a member carried by the spout adapted to over-lie said air valve when the spout is turned to its sealed position.

3. A faucet for liquid containers comprising a housing, a passageway through said housing, a stop cock mounted in the housing controlling the flow of liquid therethrough, a spigot mounted in the housing forward of the stop cock, a spout carried by the spigot and a passageway through the spigot adapted to communicate with the first mentioned passageway when the spout is turned to its dispensing position, a mounting for said housing, an air valve carried by said mounting and a member carried by the spout adapted to over-lie and surround said air valve when the spout is turned to its sealed position.

4. A faucet for liquid containers comprising a

housing, a passageway through said housing, a stop cock mounted in the housing controlling the flow of liquid therethrough, a handle mounted in the housing controlling the flow of liquid therethrough, a handle carried by said stop cock, a spigot mounted in the housing forward of the stop cock, a spout carried by the spigot characterized in that the spout and handle can be sealed together preventing the movement of either to withdraw liquid from the container without breaking the seal, a mounting for said housing, an air valve carried by said mounting and a member carried by the spout adapted to over-lie said air valve when the spout is turned to its sealed position.

5. A faucet for liquid containers comprising a housing, a passageway through said housing, a stop cock mounted in the housing controlling the flow of liquid therethrough, a handle carried by 10 said stop cock, a spigot mounted in the housing forward of the stop cock, a spout carried by the spigot, a passageway through said spigot and spout adapted to communicate with the first mentioned passageway when the spout is turned to its dispensing position, said spout being adapted 15 to lie against the handle when the stop cock is in closed position, means for sealing the spout and handle in said position, a mounting for said housing, an air valve carried by said mounting and a member carried by the spout adapted to 20 over-lie said air valve when the spout is turned to its sealed position.

6. A faucet for liquid containers comprising a

housing, a passageway through said housing, a stop cock mounted in the housing controlling the flow of liquid therethrough, a spigot mounted in the housing forward of the stop cock, a spout carried by the spigot, the spout being disposed below the rim of the container during storage or shipment and adapted to be swung over the rim of the container to a pouring position, a mounting for said housing, an air valve carried by said mounting, a member carried by the spout adapted to over-lie said air valve when the spout is turned to its sealing position, said air valve being disposed in the mounting so as to prevent the removal of the housing therefrom without removing said air valve.

7. A faucet for liquid containers comprising a housing, a passageway through said housing, a stop cock mounted in the housing controlling the flow of liquid therethrough, a spigot mounted in the housing forward of the stop cock, a spout carried by the spigot and a passageway through the spigot adapted to communicate with the first mentioned passageway when the spout is turned to its dispensing position, a mounting for said housing, an air valve carried by said mounting and a member carried by the spout adapted to over-lie said air valve when the spout is turned to its sealing position, said air valve being disposed in the mounting so as to prevent the removal of the housing therefrom without removing said air valve.

HENRY HUGHES.
